UNITED STATES PATENT OFFICE.

PAULINE B. BOWEN, OF MINNEAPOLIS, MINNESOTA.

DESIGN FOR A VANITY PURSE.

Application filed February 28, 1927. Serial No. 20,924. Term of patent 3½ years.

To all whom it may concern:

Be it known that I, PAULINE B. BOWEN, a citizen of the United States, residing at Minneapolis, in the county of Hennepin and State of Minnesota, have invented a new, original, and ornamental Design for Vanity Purses, of which the following is a specification, reference being had to the accompanying drawing, forming part thereof.

Fig. 1 is a face view of a vanity purse showing my new design.

Fig. 2 is a left hand end elevation of Fig. 1 and Fig. 3 is a back view of my new design.

I claim:

The ornamental design for a vanity purse as shown.

PAULINE B. BOWEN.
